FIG. 7 is a left side elevation view thereof;

FIG. 8 is a top plan view thereof;

FIG. 9 is a bottom plan view thereof;

FIG. 10 is a first perspective view of a second embodiment of an electric vehicle charging station with a charger handle connected;

FIG. 11 is a second perspective view thereof;

FIG. 12 is a third perspective view thereof with the charger handle disconnected;

FIG. 13 is a front elevation view thereof;

FIG. 14 is a rear elevation view thereof;

FIG. 15 is a right side elevation view thereof;

FIG. 16 is a left side elevation view thereof;

FIG. 17 is a top plan view thereof;

FIG. 18 is a bottom plan view thereof;

FIG. 19 is a first perspective view of a third embodiment of an electric vehicle charging station with a charger handle connected;

FIG. 20 is a second perspective view thereof;

(Continued)

FIG. 21 is a third perspective view thereof with the charger handle disconnected;
 FIG. 22 is a front elevation view thereof;
 FIG. 23 is a rear elevation view thereof;
